INVENTOR

Oscar Zerk.

UNITED STATES PATENT OFFICE.

OSCAR ZERK, OF CLEVELAND, OHIO, ASSIGNOR TO THE ZERK MANUFACTURING COMPANY, OF CLEVELAND, OHIO, A CORPORATION OF OHIO.

GREASE-CUP.

1,029,412.

Specification of Letters Patent. Patented June 11, 1912.

Application filed September 2, 1910. Serial No. 580,217.

To all whom it may concern:

- Be it known that I, OSCAR ZERK, a subject of the Emperor of Austria-Hungary, residing at Cleveland, in the county of Cuyahoga and State of Ohio, have invented a certain new and useful Improvement in Grease-Cups, of which the following is a full, clear, and exact description, reference being had to the accompanying drawings.
- 10 This invention relates to grease cups of the type wherein there is a member having a tubular opening communicating with the bearing and formed with a surface adapted to support the grease, and a cap screwing onto such member and adapted to force the grease through the opening, there being a spring detent to prevent inopportune displacement of the cap.
- 15 The object of the invention is to simplify and cheapen the construction of such grease cup and to render it more efficient.

To the above mentioned ends I make the stationary member, commonly called the cup, in a form which may be stamped and 25 having a non-circular bore, and I provide a tongue occupying such bore and connected with a head within the cap above the grease, and a suitable spring adapted to restrict the 30 free rotation between the tongue and the cap. This spring I form in a peculiar manner, which increases its efficiency and durability, while allowing it to be carried with the greatest convenience within the cap.

The characteristics of the invention may 35 be best summarized as consisting of the combinations of elements hereinafter described and summarized in the claims.

The drawings clearly illustrate my invention.

40 Figure 1 is a side elevation of the grease cup complete; Fig. 2 is a vertical sectional section thereof; Fig. 3 is a bottom plan; Fig. 4 is a cross section through the cap looking upward, as indicated by the line 45 A—A; Fig. 5 is a cross section in a similar plane looking downward; Fig. 6 is a perspective of the spring detached; Fig. 7 is an enlarged detail, in section, of parts adjacent to the upper end of the cap.

Referring by reference numerals to the construction shown, 10 represents the member which is called the cup. This member is a metal stamping and has an externally threaded bottom portion 11, a portion above

this having a non-circular bore, preferably 55 a square bore, as shown at 12, and above the upper end of this portion is an outwardly extending annular portion 13, from which extends a downward flange 14, which is screw-threaded on its exterior. The bore 12 60 is continued, preferably in the form of a tapered bore 15, through the threaded end 11 to the end of the cup. The top surface of the annular portion 13, together with the angular bore and the tapered bore carry the 65 grease.

The cap is designated 20. It has a cylindrical wall internally threaded substantially throughout, and a top plate 21. Where these join, there is an outward bead, which 70 is made into a series of projections 22 having radial walls by being slotted across. This provides efficient means whereby the cap may be grasped and turned. The cap is preferably a stamping, and the projections are preferably made by a punch, 75 punching through the bead formed by the stamping.

30 designates a thin, flat tongue, which preferably has a widened lower end 31, 80 which stands diagonally within the square bore 12. The widened portion of the tongue is of greater width than a side of the square bore, (being preferably of just slightly less width than the diagonal of the bore) wherefore this tongue may move up and down in the bore, but cannot rotate therein. At its upper end, the tongue is swiveled in a disk 40, which is slightly concaved upwardly and rests against the under surface of the top 90 of the cap. This swiveling may be easily accomplished by simply upsetting the upper end of a central projection 32 extending upwardly from the top, the hole in the disk which the projection occupies preferably 95 flaring upwardly.

50 designates a spring, which lies within the cap beneath the disk 40 and has arms 51 engaging the tongue 30. The resilience of this spring compels it to rotate with the 100 cap, and, as the tongue cannot rotate, the spring, during the rotation, is forced backwardly by the tongue and then springs against the opposite side, with the result that the cap may be rotated in periodic 105 steps, half a rotation each. The spring 50, in order to be effective and insure long life, has a coil 52 on each side between the cir-

cular portion and the projecting parts 51. This enables the spring to have sufficient force against the tongue and still have sufficient resilience to allow the cap to be turned, 5 as desired, while such turning movement does not bend the spring about a single line, but throughout the whole coil 52. A very durable spring is thus provided. The spring occupies a slight depression or recess 53 in 10 the wall of the cap above the threads. By having the tongue narrower where the spring engages it than where it engages the square bore, the bore may be comparatively large and at the same time the restraining 15 effect of the spring not be excessive.

With my grease cup, the parts are formed with a maximum of simplicity and cheapness, the cup, the cap, the tongue and the head may each be a stamping made with 20 great cheapness, and the spring, while very effective, as described, is also simple and cheaply constructed. The parts are very easily assembled, the upsetting of the end of the projection 32 swiveling the tongue to 25 the disk, and the insertion of the spring holding these parts in place.

Having thus described my invention, what I claim is:—

1. In a grease cup, the combination, with 30 a cup member and a cap member screwing one onto the other, of a tongue and a spring mounted in and carried by one and the same member, the spring frictionally bearing on the tongue, whereby the movable member is held against premature movement and the tongue slides but does not rotate in the other member.

2. In a grease cup, the combination, with 40 a cup member and a cap member screwing one onto the other, of a tongue slidable but non-rotatable in one member, and a spring mounted within the other member and having a pair of arms engaging the opposite sides of said tongue, said arms being connected with the bowed portion of the spring through the intermediary of coils.

3. In a grease cup, the combination, with 50 a cup member having external threads and a cap member having internal threads screwing onto the cup member, of a flat tongue slidable but non-rotatable in a non-circular bore of the cup member, and a spring mounted within the cap member and having a pair of arms engaging the opposite sides of said tongue, said arms being connected with the bowed portion of the spring through the intermediary of coils.

4. In a grease cup, the combination of a 60 cup having a non-circular bore and a threaded exterior and a cap having a threaded interior and screwing onto the cup, a disk within the cap at its upper end, a tongue swiveled in said disk and occupying a diagonal position in the square bore, and a spring rotatable with the cap 65 and frictionally engaging the tongue.

5. In a grease cup, the combination of a cup having a square bore and a threaded exterior and a cap having a threaded interior and screwing onto the cup, a disk within the cap at its upper end, a flat tongue swiveled to 70 said disk and occupying a diagonal position in the square bore, and a spring frictionally engaging the flat side of the tongue.

6. In a grease cup, the combination of a cup having a non-circular bore and a threaded exterior, a cap having a threaded interior and screwing onto the cup, a disk within the cap at its upper end, a tongue swiveled in 75 said disk and occupying the bore, and a spring within the cap engaging the tongue, 80 said spring occupying a recess in the inner wall of the cap and standing beneath the disk and serving the double purpose of holding the disk in place and retarding the rotation of the cap independently of the tongue. 85

7. In a grease cup, the combination of a cup having a non-circular bore and a threaded exterior, a cap having a threaded interior and screwing onto the cup, a disk within the cap at its upper end, a flat tongue swiveled 90 in said disk and occupying the bore, a spring within the cap engaging the tongue, said spring occupying a recess in the wall of the cap and having a bowed intermediate portion and two arms standing respectively on 95 opposite sides of the tongue, each arm being connected with the bowed portion by a coil.

8. In a grease cup, the combination, with a cup member externally threaded, a cap member internally threaded and screwing 100 onto the cup member, a tongue slidably and non-rotatably mounted in the non-circular bore of the cup member, and a spring carried by the cap member and frictionally bearing against the tongue. 105

9. In a grease cup, the combination of a cup member externally threaded, a cap member internally threaded and screwing onto the cup member, a tongue rotatably carried by the cap member and non-rotatably but 110 slidably engaging the bore of the cup member, and a spring carried by the cap member and bearing against the tongue.

10. In a grease cup, the combination of a cup having a square bore and a threaded exterior and a cap having a threaded interior and screwing onto the cup, a disk within the cap at its upper ends, a flat tongue swiveled to 115 said disk and having a wider head occupying a diagonal position in the square bore, 120 and a spring having two projecting arms engaging opposite sides of the tongue above the head therein.

11. In a grease cup, the combination of a cup member externally threaded, a coöperating cap member internally threaded, a tongue slidably but non-rotatably engaging in the bore of the cup member, means carried by the cap member for supporting such tongue, and a spring carried by the cap 130

member bearing against the side of the tongue and restricting rotation between the cap member and the tongue.

12. In a grease cup, the combination of a cup externally threaded, a coöperating cap internally threaded, a tongue slidably engaging the angular bore of the cup, a disk in which the upper end of the tongue is swiveled, and a spring occupying an annular recess in the inner wall of the cap near its upper end and serving to hold the disk in place, said spring also having a pair of arms bearing against the opposite sides of the tongue.

13. In a grease cup, the combination of a

cup having a non-circular bore and external threads, a cap internally threaded and screwing onto the cup, a tongue having a non-circular sliding engagement with the bore, means for supporting said tongue by 20 the cap while allowing the cap to rotate with reference to the tongue, and a spring engaging the cap and tongue and retarding the independent rotation of the cap.

In testimony whereof, I hereunto affix my 25 signature in the presence of two witnesses.

OSCAR ZERK.
